UNITED STATES PATENT OFFICE

118,011

DESIGN FOR A REBOUND DEVICE FOR A
PIN-BALL GAME APPARATUS

Charles E. Caestecker, Chicago, Ill.

Application October 9, 1939, Serial No. 87,586

Term of patent 14 years

To all whom it may concern:

Be it known that I, Charles E. Caestecker, a citizen of the United States, residing at Chicago, in the county of Cook and State of Illinois, have invented a new, original, and ornamental Design for a Rebound Device for a Pin-Ball Game Apparatus, of which the following is a specification, reference being had to the accompanying drawing, forming a part thereof.

In the drawing:

Fig. 1 is a perspective view of a rebound device for a pin-ball game apparatus showing my new design.

Fig. 2 is a top plan view thereof; and
Fig. 3 is an end elevational view.

I claim:

The ornamental design for a rebound device for a pin-ball game apparatus, substantially as shown.

CHARLES E. CAESTECKER.
